ATTORNEY

UNITED STATES PATENT OFFICE.

CHARLES GATES, OF LEBANON, PENNSYLVANIA.

COMBINED PLUMB, LEVEL, AND SQUARE.

SPECIFICATION forming part of Letters Patent No. 339,287, dated April 6, 1886.

Application filed January 18, 1886. Serial No. 188,921. (No model.)

To all whom it may concern:

Be it known that I, CHARLES GATES, a citizen of the United States, residing at Lebanon, in the county of Lebanon and State of Pennsylvania, have invented certain new and useful Improvements in Combined Plumb, Level, and Square; and I do hereby declare the following to be a full, clear, and exact description of the invention, such as will enable others skilled in the art to which it appertains to make and use the same.

This invention relates to a combined tool or implement designed specially for the use of masons, bricklayers, and carpenters, but is not limited thereto, as it is of general application; and it consists in the constructions hereinafter described, and particularly pointed out in the claims.

In the accompanying drawings, which form a part of this specification, Figure 1 represents a plan showing the upper end in position to form a square in dotted lines; Fig. 2, a perspective detail of sliding block and dovetail seat; Fig. 3, a detail perspective of hinge-joint; Fig. 4, a section on line *a a*; Fig. 5, a sectional detail of spring-catch; and Fig. 6, a detail perspective, showing spirit-level.

Reference being had to the drawings and the letters of reference marked thereon, A represents a graduated plumb-level made in two sections, and provided with a hinge, B, for the purpose of converting it into a square. The hinge is of ordinary construction common to carpenters' rules. Between the two sections of the hinge is interposed a sector-plate, *a*, of metal, provided with flanges *b c*, projecting from opposite sides of the plate, as shown in Fig. 4. The adjacent ends of the instrument are provided with slots *d e*, into which the plate *a* projects, and upon both sides of said ends are secured metal plates *f*, having flange *g*, which extends down to form a bearing against the flanges *b c* of the plate *a*, as shown in Fig. 4, and support the upper end of the instrument when it is turned at a right angle to its companion piece to form a square, as shown in dotted lines in Fig. 1 and in full lines in Fig. 3.

When the two parts of the instrument are in line to form a plumb or level, they are se-

curely locked by means of a projection, *h*, on the upper section and a corresponding projection, *i*, on a leaf-spring, *j*, provided with a push-button, *k*, secured to the lower section, as shown in Fig. 5.

Upon the upper end of the instrument is secured a plate, *l*, having a dovetail groove formed in it to receive a corresponding block, *m*, which is provided with a stud or post, *n*, having a slot in it to receive a plumb-line. The block *m* is adjustable in the slot for the purpose of setting the plumb-line at any angle of inclination desired in building inclined walls, and enables the user to set the plumb to a scale giving any desired angle or inclination to the running foot, as indicated by the dotted lines *o p*. The block is secured in any desired position by a screw, *q*.

C represents a tube containing mercury or spirit, and *D D* are hand-holes.

Plumb-levels as ordinarily constructed are very apt to fall when set upon end, which frequently results in breaking the glass containing the spirit. To provide against this evil I insert a pin, *r*, in the lower end of the instrument, which when the instrument is set upon that end embeds itself in the ground, the scaffolding, or a floor, and prevents its slipping.

E is a plumb-bob attached to a line, *s*, which is held in the slotted stud or post *n*.

I am aware that a surveyor's instrument mounted upon a tripod has been provided with an adjustable plate, to which the line of a plumb-bob has been attached, and do not therefore claim such matter as my invention.

Having thus fully described my invention, what I claim is—

1. A rectangular plumb-level having a groove or seat in one end thereof, in combination with a head or block provided with a line-support and adapted to slide in said groove, substantially as described.

2. A rectangular plumb-level having a groove or seat in one end thereof, in combination with a head or block provided with a line-support and a locking device, substantially as described.

3. A plumb-level formed in two sections, arranged in the same plane, and provided with a hinge on one side, in combination with

flanged end plates connected to the upper section, and a flanged sector-plate for supporting the upper section when in position to form a square, substantially as described.

5 4. A plumb-level formed in two sections, and provided with a hinge, a flanged sector-plate, and flanged end plates, in combination with an automatic locking device, substantially as described.

In testimony whereof I affix my signature in presence of two witnesses.

CHARLES GATES.
